QUICK-RELEASE STRAP FASTENER

Winniefred Faire Houghton, Arlington, Va.

Application June 4, 1936, Serial No. 83,569

2 Claims. (Cl. 24—193)

The invention forming the subject of this application relates to improvements in quick-release fastening devices of the type wherein two or more rings or buckles cooperate for adjustably securing a shoulder strap or the like, with a garment to be suspended therefrom.

The main object of the invention is to provide a fastener for shoulder straps and the like which not only permits a quick and practically instantaneous release of the straps, but also permits a slow release of the same whenever desired.

A further object of the invention is to provide the cooperating buckles or members of fastening devices of the character described with means to clamp said members in adjusted position to prevent undesirable slipping or loosening of the straps when the tension thereon is removed.

Other objects of the invention will become apparent as the detailed description thereof proceeds.

In the drawing:

Figure 1 is a front elevation of the quick-release fastening devices shown in locking position;

Figure 2 is a vertical transverse section to an enlarged scale taken on the line 2—2 of Figure 1;

Figure 3 is an exploded perspective of the cooperating fastening elements illustrated in Figures 1 and 2; and

Figure 4 is a front elevation of a modified form of the cooperating fastening elements shown in Figures 1, 2, and 3.

As shown in Figures 1, 2, and 3 of the drawing, the invention comprises two members designated generally by the reference numerals 1 and 2. The member 1 comprises a substantially rectangular frame having side members 3 and 4 connected at their top and bottom ends by cross bars 5 and 6, respectively, the bottom member 6 being provided with serrations 7 adapted to form a gripping edge for a strap or the like connected thereto.

The side 3 of the member 1 is continued upwardly beyond the bar 5 by an extension 8. From the upper end of the extension 8 a third bar 9 extends parallel to the bars 5 and 6 and terminates in a lug 10 projecting toward the bar 5 and aligned substantially with the side 4 of the member 1.

The member 2 comprises a substantially rectangular frame having sides 11 and 12 connected at their upper ends by a bar 13, the upper edge of which is provided with serrations 14 to form an effective gripping edge for a strap or the like connected thereto. The lower ends of the sides 11 and 12 are connected by a bar 15 substantially

parallel to the bar 13. The frame thus formed by the sides 11 and 12 and the bars 13 and 15 of the member 2 are substantially the same in size as the frame formed by the sides 3 and 4 and the bars 5 and 6 of the member 1. The lower end of the member 2 is provided with tabs 16 and 17 projecting upwardly from said lower edge in the direction of the sides 11 and 12, respectively, but spaced therefrom sufficiently to receive frictionally between them the sides 11 and 12 and the lower end of the member 1.

The members 1 and 2 are connected for fastening purposes in the manner illustrated in Figures 1 and 2 of the drawing. The strap 18 is formed as a loop around the bar 13 of the member 2. The two plies formed by this loop are next passed over the front face of the bar 5 in member 1, and are then drawn over the rear face of the bar 9 of member 1.

As shown in Figure 2 the member 2 is arranged with its front face against the rear face of member 1. The other strap 19 to be secured in adjusted relation to strap 18 is looped around the bar 6 of member 1 and the plies formed by this loop are then drawn over the upper edge of bar 15 of member 2 and across the rear face thereof.

It will be apparent from Figure 2 of the drawing that when the straps 18 and 19 are under tension, the upper part of member 2 will be drawn tightly against the rear face of member 1 near the bar 5 thereof. At the same time the tension on strap 19 pulls the lower part of member 1 tightly against the front face of the member 2 near the lower end thereof. So long as these members 1 and 2 are thus held in contact, it will be obvious that the straps 18 and 19 will be held locked in relatively adjusted position.

It will also be apparent from the drawing that when the straps 18 and 19 are tensioned as shown in Figure 2, the lower end of member 1 will be seated between the tabs 16 and 17 and the front face of member 2. This engagement of the members 1 and 2 will prevent any undesirable or accidental separation of the members 1 and 2 with consequent release of the straps.

The modification shown in Figure 4 of the drawing is the same in principle of operation as the form shown in Figures 1, 2, and 3. The elements of Figure 4 corresponding to equivalent elements in Figures 1, 2, and 3, are indicated by the same reference numerals primed. It is believed the operation of this form of the invention will also be apparent without further description.

It is to be understood that the invention is not

to be considered as limited to the specific construction and arrangement described herein, since it is evident that many changes may be made without departing from the scope of the invention as defined by the claims appended hereto.

What I claim is:

1. A fastener of the character described comprising a buckle member having three spaced apart strap receiving bars, and a second member 10 having strap receiving bars spaced apart at a distance substantially equal to the spacing between two of the first named bars, straps looped around the bars of said members and locked thereby in relatively adjusted position by tension applied to 15 said straps, and means for clamping said mem-

bers to each other when tension is applied to said straps.

2. A fastener of the character described comprising a buckle member having three spaced apart strap receiving bars, and a second member 5 having strap receiving bars spaced apart at a distance substantially equal to the spacing between two of the first named bars, straps looped around the bars of said members and locked thereby in relatively adjusted position by tension 10 applied to said straps, and clamping tabs on one end of the second member to receive the corresponding end of the first member when tension is applied to said straps.

WINNIFRED FAIRE HOUGHTON. 15
